MERCHANDISE DISPLAY BOOTH OR SIMILAR ARTICLE

Russell T. Martin and Lewis R. Stone, Los Angeles, Calif.

Application January 13, 1955, Serial No. 33,963

Term of patent 14 years

(Cl. D80—11)

FIG. 1.

To all whom it may concern:

Be it known that we, Russell T. Martin and Lewis R. Stone, both citizens of the United States, residing at Los Angeles, in the county of Los Angeles and State of California, have invented a new, original, and ornamental Design for a Merchandise Display Booth or Similar Article, of which the following is a specification, reference being had to the accompanying drawing forming part thereof, in which:

Fig. 1 is a perspective view of a merchandise display booth showing our new design; and

Fig. 2 is a front elevational view thereof.

We claim:

The ornamental design for a merchandise display booth or similar article, substantially as shown.
